UNITED STATES PATENT OFFICE.

ADDISON O. BONIFACE, OF UTICA, NEW YORK, ASSIGNOR, BY MESNE ASSIGNMENTS, TO AMERICAN LA FRANCE AND FOAMITE CORPORATION, A CORPORATION OF NEW YORK.

FOAM-TYPE FIRE EXTINGUISHER.

Application filed December 29, 1924. Serial No. 758,518.

The invention relates to invertible foam-type extinguishers of the kind in which the inner receptacle is normally closed by a gravity-seated stopple intended to fall open on inversion. The object is to eliminate the tendency for the stopple to stick to its seat. Such sticking occurs from the penetration of the foam solutions, one or both, into the crevice between the seat surfaces and the eventual formation thereby of a crust or deposit which is often sufficient to hold the stopple closed, rendering the extinguisher useless in time of fire.

The present invention consists in a structure in which the stopple makes contact of small area with the side as well as the top of the stopple seat so that the risk of sticking from incrustation is reduced to a minimum under all conditions, as for example when the stopple has been displaced sidewise to the extent of the lateral movement permitted to it. Under such conditions and even where the support of the stopple in a vertical sense is by a minimum contact area, sticking may still occur as the result of a deposit or crust forming elsewhere, that is to say, between a marginal portion of the stopple and a proximate vertical surface.

The accompanying drawing shows the form of the invention at present preferred, Fig. 1 being a side elevation of a foam-type extinguisher of familiar design, partly broken open;

Figure 2 a larger scale axial section through the seat ring and stopple;

Figure 3 a bottom plan of the stopple;

Figure 4 a side elevation with part in section, and

Figure 5 a detail vertical section of a form preferred to that shown in the other figures.

The general construction and mode of operation of the extinguisher will be recognized without description. The inner receptacle 1 is provided with an annular seat ring 2 secured therein, just below the level of the port openings 3 and extending upwardly above such level where its upper edge forms the stopple seat. This upper edge is preferably formed with a sharp bevel, but this is not essential, especially if the seat ring is stamped up out of sheet metal, as shown in Fig. 5, which is ordinarily thin enough for the purpose without bevelling. The upward extension of the seat ring above the ports 3, pro-

vides for the prompt drainage away from it of any liquid in the upper receptacle that may splash upon it.

The illustrated stopple is provided on its under surface with a number of radial ribs 4 of sharp or rounded contour by means of which it rests upon the sharp or thin upper edge of the seat ring, thus producing point bearings with a minimum possibility of sticking. In the present case there are four such ribs and points of bearing, symmetrically arranged, but a less number would obviously suffice. The stopple is held against lateral displacement on the seat so that it will not touch the surrounding portions of the receptacle, or cage-bars, between the port-openings 3, to which it might become stuck by incrustation and for this purpose a part of the stopple extends below the top of the seat, either on the inside or the outside; such part is adapted to have lateral contact with the seat to prevent the stopple from excessive lateral movement thereon and also to assist in guiding it to a properly centralized position when it is put in place. In Fig. 2 the peripheral flange 5 serves this purpose as well as the further purpose of protecting the seat from splashed liquid. In Fig. 5 the main body part of the stopple projects into the inner container for the same purpose, the flange 5 in this case serving merely to protect the seat against splash. In either case the lateral contact between the depending part, flange or central body part as the case may be, is rendered safe from sticking by incrustation by providing such part with ribs or projections marked 6 in the case of Figs. 2 and 9 in the case of Fig. 5. Each of these ribs is arranged to make a point contact with the side (inside or outside) of the seat ring and such point contact is the least likely to induce the formation of an objectionable adhesion by incrustation. The new stopple is thus guarded against making any other than point contacts with its seat, whether placed exactly central on the seat or whether pushed to one side or the other while resting upon it and in consequence, the danger of failure from sticking of the stopple is reduced to a minimum. Preferably the ribs, 6 or 9, are inclined in order to assist in guiding the stopple to a central position as well as to facilitate manufacture.

The stopple is ordinarily made as a cast-

ing of lead or lead alloy and the ribs and flange referred to are thus easily produced with no increase of expense over the stopples now generally in use. It is preferred to 5 form the stopple with a central upstanding top lug 7 which is initially cast of the triangular shape shown by the dotted lines and thereafter upset, by a hammer stroke, to produce the cross sectional shape indicated in 10 Fig 4, thereby giving the lug a widened top and constituting it as a handle by means of which the stopple can be lifted out of the container.

I claim—

- 15 1. In a foam-type invertible extinguisher, an inner receptacle having a stopple seat, and a gravity stopple therefor having an upper part adapted to seat vertically on the stopple seat and a lower part having a plurality of 20 projections adapted to make contact of small area with the side of the stopple seat.
2. In a foam-type invertible extinguisher, an inner receptacle having a stopple seat, and a gravity stopple therefor having an upper 25 seating part adapted to rest vertically on the seat and a lower centering part provided with inclined ribs adapted for lateral contact with the side of said seat, each such rib forming only a contact of small area.

3. In a foam-type invertible extinguisher, 30 an inner receptacle having a stopple seat, and a gravity stopple therefor having an upper seating part adapted to rest vertically on the stopple seat and a central centering part provided with inclined ribs adapted for contact with the inner side of the seat on lateral movement of the stopple on the seat.

4. In a foam-type invertible extinguisher, 40 an inner receptacle having a stopple seat, and a gravity stopple therefor having an upper seating part adapted to rest vertically on said seat and having other than a line-contact with said seat, and a lower centering part provided with inclined ribs adapted for lateral contact with the side of said seat, each 45 such rib forming only a contact of small area.

5. In a foam-type invertible extinguisher, 50 an inner receptacle having a stopple seat, and a gravity stopple therefor adapted to seat vertically on the stopple seat and having an exterior flange and a plurality of projections adapted to make contact of small area with the side of the stopple seat.

In testimony whereof, I have signed this 55 specification.

ADDISON O. BONIFACE.
